[57] CLAIM

The ornamental design for a carrying case for compact discs or the like, as shown and described.

DESCRIPTION

FIG. 1 is a perspective view of a carrying case for compact discs or the like showing my new design; FIG. 2 is a top plan view thereof;

FIG. 3 is a right side elevational view thereof, the left side being a mirror image;

FIG. 4 is a rear elevational view thereof;

FIG. 5 is a front elevational view thereof; and

FIG. 6 is a bottom plan view thereof.

FIG. 1

FIG. 2

FIG. 3

FIG. 4

FIG. 5

FIG. 6
